UNITED STATES PATENT OFFICE

CLARENCE W. STEELE, OF MELROSE, AND DAVID I. LEVINE, OF WAKEFIELD, MASSACHUSETTS, ASSIGNORS TO HEYWOOD-WAKEFIELD COMPANY, OF BOSTON, MASSACHUSETTS, A CORPORATION OF MASSACHUSETTS

SPRING UNIT FOR CHAIR SEAT FRAMES

Application filed February 10, 1931. Serial No. 514,759.

This invention relates to a spring unit which with other similar units is adapted to be secured in the frame of a seat. According to the invention a spring unit is provided which may be made chiefly of iron strap or other suitable metal, together with a suitable number of springs.

For a more complete understanding of the invention reference may be had to the disclosure thereof in the following description and on the drawing, of which,—

Figure 1 is a plan view of a frame for a chair seat including an embodiment of the invention.

Figure 2 is a section on the line 2—2 of Figure 1.

Figure 3 is a fragmentary view similar to Figure 2 showing the movable parts in a different position of operation.

Figure 4 is a section on the line 4—4 of Figure 1.

A rectangular frame for a chair seat is illustrated in Figure 1. This may consist of four side bars 10, 11, 12 and 13 supported by suitable legs 14 at the corners of the frame. Between two opposite side bars such as 10 and 12 are strung a suitable number of spring units, one such unit being illustrated in Figure 2. Each of these units may consist of a stiff strap 20, preferably of relatively heavy metal stock. This strap is formed with a depressed lower portion 21, from which its end portions 22 and 23 slope upwardly as shown. Horizontally disposed above this strap is a flexible strap 24 the end portions of which are turned under as at 25 to lap under the end portions of the strap 20 and to be secured thereto. The turned under portions 25 of the upper strap are preferably of spring metal, so that when the central portion of the flexible strap 24 is depressed, as when a weight is put upon the chair seat, the resilient turned under end portions 25 of the flexible strap are adapted to yield. As shown on the drawing, the entire flexible strap 24 may consist of a single strip of thin, flexible steel, the end portions of which are turned under. Between the straps 20 and 24 are a number of compression springs 30, two such springs being illustrated in the unit

shown on the drawing. These springs may be of any type suitable for compressive resistance, the well known helical type being illustrated by way of example. The lower end of each spring is suitably secured to the depressed portion of the strap 20, the upper end of each spring being secured to the flexible strap 24.

For the support of each unit, a pair of hangers 31 may be provided. Each hanger 31 may consist of a piece of metal stock which may be similar to the stock used for the stiff strap 20. Each hanger may be shaped as shown in Figure 3, with one end portion 32 horizontally disposed and adapted to be fastened by a wood screw or otherwise on the upper surface of one of the side members of the chair frame. The other end portion 33 of the hanger extends rearwardly from the frame and downwardly to lap the upwardly extending adjacent end of the stiff strap 20, to which it is secured. Thus the end portions of the three members 20, 24 and 31 may all be secured together in face to face relation, the end portion of the flexible strap 24 being between the end portions of the members 20 and 31, as shown in Figure 3. These end portions may be secured together as by a rivet 34 which passes through all of them, or in any other convenient and suitable manner. The end of the stiff member 20, resting upon the end of the strap 24, provides efficient support for the turned under portion 25. This arrangement also results in the end portion of the thin metal strap being clamped between the heavier straps so that there is no danger of the thin metal being torn away from the rivet. When a weight is placed upon the flexible element 24 so as to depress the same against the springs 30, the turned under portions 25 are able to yield sufficiently to permit the necessary sag in the middle of the flexible strap, as shown in Figure 3, without resulting in excessive stresses being imposed on the hangers 31. Since the strap 20 is preferably somewhat stiff and rigid, the resultant stresses on the hangers 31 are chiefly downward rather than inward, so that there is little tendency on the part of the hangers to

- pull away from the supporting members of the frame. To provide lateral support for the flexible members 24, a number of suitable links 40 may be employed between successive flexible straps. These links may be made of stiff wire or the like, the ends of which are bent back through suitable holes in the flexible straps 24. Thus each of the flexible straps is laterally supported by all the others so as to prevent lateral yielding when a weight is placed on one or more of the spring units.
- We claim:
1. A spring unit comprising a stiff metal strap having a depressed central portion and upwardly sloping end portions, a flexible strap extending horizontally above said stiff strap and having resilient end portions curved downwardly to lap under the ends of the stiff strap, a pair of hangers adapted to support the respective ends of the straps, each said hanger having a portion abutting the under-turned end portion of the flexible strap, means fastening each hanger to the adjacent end portions of said straps, and compression springs extending between the central portions of said straps.
  2. A spring unit for a chair seat, comprising a stiff metal strap having a depressed central portion and upwardly sloping end portions, a hanger at each end of said strap consisting of a piece of similar metal stock having one end portion lapping below the adjacent end portion of said strap and secured thereto, the other end of each said hanger being adapted to be secured to a chair frame, a flexible spring metal strap of thinner stock horizontally disposed above said stiff strap, said thin strap having its end portions curved downwardly and secured face to face between the adjacent lapped end portions of the stiff strap and hanger, and a plurality of compression springs each having its lower end secured to said stiff strap and its upper end secured to said flexible strap.
  3. A support for a chair seat, comprising a rectangular frame, a plurality of spring units slung between two sides of said frame, each said unit consisting of a pair of hangers, each having one end secured to a side of said frame and the other end extending inwardly and downwardly, a flexible spring strap disposed horizontally, said strap having its end portions turned under and secured against the upper faces of the respective hangers, a stiff strap having its end portions secured upon respective end portions of said flexible strap, said stiff strap having a central portion spaced below said flexible strap, and a plurality of compression springs secured between said straps; and lateral connecting means between adjacent units consisting of stiff wires linked at their ends to successive flexible straps.
  4. A spring unit comprising a relatively

stiff strap having a depressed central portion, upwardly extending portions adjoining said central portion, and elevated end portions, and a relatively flexible strap horizontally extended above said central portion, the ends of said flexible strap being turned under and secured respectively to the upwardly extending portions of the stiff strap.

5. A spring unit comprising a relatively stiff strap having a depressed central portion, upwardly extending portions adjoining said central portion, and elevated end portions, a relatively flexible strap horizontally extended above said central portion, the ends of said flexible strap being turned under and secured respectively to the upwardly extending portions of the stiff strap, and a compression spring mounted between said central portion and said flexible strap.

6. A spring unit comprising a relatively stiff strap having a depressed central portion, upwardly extending portions adjoining said central portion, and elevated end portions, and a relatively flexible strap horizontally extended above said central portion, the ends of said flexible strap being turned under and secured respectively to the upwardly extending portions of the stiff strap, said stiff strap including clamping portions bearing on substantial areas of the opposite faces of each end portion of said flexible strap.

7. A spring unit comprising a relatively stiff strap consisting of three pieces permanently secured together by lap-joints to form a single length, said strap having a depressed central portion, upwardly extending portions adjoining said central portion, and elevated end portions, said lap-joints being in said upwardly extending portions, and a comparatively flexible strap horizontally extended above said stiff strap, the end portions of said flexible strap being turned under and permanently secured respectively in said lap-joints.

In testimony whereof we have affixed our signatures.

CLARENCE W. STEELE.
DAVID I. LEVINE.
